UNITED STATES PATENT OFFICE.

GEORGE D. GALLAGHER, OF WASHINGTON, DISTRICT OF COLUMBIA, ASSIGNOR, BY MESNE ASSIGNMENTS, OF TWENTY-FIVE ONE HUNDRED AND FOURTHS TO NANNIE T. HOOS, TWENTY-FIVE ONE HUNDRED AND FOURTHS TO RUTH B. WALLEN, FOUR ONE HUNDRED AND FOURTHS TO MARGUERITE G. SCHANBERGER, ALL OF BALTIMORE, MARYLAND, TWENTY-FIVE ONE HUNDRED AND FOURTHS TO CALLIE F. MOORE, OF WASHINGTON, DISTRICT OF COLUMBIA, AND TWENTY-FIVE ONE HUNDRED AND FOURTHS TO J. MARSH MATTHEWS, OF BALTIMORE COUNTY, MARYLAND.

SAFETY-RAZOR-BLADE STROPPER.

Application filed September 22, 1921. Serial No. 502,479.

To all whom it may concern:

Be it known that I, GEORGE D. GALLAGHER, a citizen of the United States, residing at Washington, District of Columbia, have invented certain new and useful Improvements in Safety-Razor-Blade Stroppers, of which the following is a description, reference being had to the accompanying drawing and to the figures of reference marked thereon.

This invention relates to razor blades stropping devices, and more particularly to improvements in the type of devices set forth in my prior Patent No. 1,319,149, granted October 21, 1919.

One of the main objects of the present invention is to provide a hand operated stropper of the before-mentioned type in which the tubular sleeves supporting the stropping rolls and through which the spiral driver reciprocates, terminate at or within the ends of the enclosing casing so that on operation of the driver they will not project as in the prior mentioned device.

A further object of this invention resides in providing such a stropper composed of a minimum number of parts which can be cheaply made and easily assembled.

Another object of this invention resides in providing a novel blade holder for holding the blade so that it will not fall off the blade holder when the latter is pulled out of the casing.

These and other objects will in part be obvious and will in part be hereinafter more fully disclosed.

Referring now to the accompanying drawings:—

Figure 1 is a plan view partly in section of one form of my improved stropper;

Fig. 2 is an end view thereof;

Fig. 3 is a section on line 3—3 of Fig. 1;

Fig. 4 is a detail perspective view of one of the slotted roll supporting tubes;

Fig. 5 is a plan view of the blade holder with the blade in held position;

Fig. 6 is a side view thereof showing the

blade in dotted outline before taking its flat position;

Fig. 7 is a perspective view of the roll supporting cage or basket, and

Fig. 8 is a modified type of stropper.

The present stropper possesses all of the simplicity of the structure disclosed in my original patent before set forth, while at the same time eliminating the projecting ends of the tubular sleeves. The device is disclosed as embodying an enclosing casing 1 suitably perforated at its ends to rotatably receive the tubes or sleeves 2 and 3. The ends of these tubes or sleeves may be turned outwardly as at 4 and 5, or may be suitably shouldered to prevent endwise movement with respect to the casing. Adjacent one end the tubes or sleeves are formed with slots 6 which are three or four in number arranged symmetrically around the circumference of the tube. Surrounding and journaled upon these tubes or sleeves 2 and 3 are the roller holding tubes 7 and 8 which are of sufficient larger diameter to fit snugly upon the tubes 2 and 3, yet permit endwise movement of the tubes 7 and 8 along the tubes 2 and 3. Preferably adjacent one end the tubes 7 and 8 are formed with an annular race-way 9 formed in any desired manner, which race-way is indented at spaced intervals as at 10, 11, 12 and 13, thereby forming individual pockets or cages for the balls 14, 15, 16 and 17. These balls pass partly through the slot 6 of the tubes or sleeves 2 and 3 and make driving engagement or contact with a spiral driver.

This driver comprises the two spiral rods 18 and 19 of desired pitch, united by the yoke or handle 20 as by the turned down ends 21 and 22 of the rods; the other ends of the spiral rods 18 and 19 are provided with turned down ends 23 over which fit the washers 24 which are preferably of a larger diameter than the diameter of the spiral portion of the rods. The ends of the turned down portions 23 are peened over to fasten the washers in place. By means of this

construction, the washers when in extreme inward position, i. e., in a position opposite to that shown in Fig. 1, are brought against the balls and thus limit further outward movement of the spiral rods. This construction prevents the blade from contacting too forcibly against the rolls.

The rolls 24, and 25 which are of wood or other suitable material, are cored out to receive the roll supporting tubes 7 and 8 and are rigidly fastened thereto as by wedging, keying or gluing. The surfaces of these rolls are suitably faced with leather 26, and 27.

15 The rolls are mounted in the basket 28 (see Fig. 7) which as shown comprises a preferably sheet metal stamping including a base portion 29 cut away as at 30 for lightness, and the end portions 31 and 32 bent at right angles. These end portions are provided with bores 33, 34, 35 and 36 to receive the tubes 7 and 8, the ends of said tubes being preferably turned outwardly as at 37 to prevent displacement. The end portion 31 is provided with a slot 38 preferably narrow, although not necessarily, while the opposite end portion 32 is formed with a bore 39 which rotatably receives one end of the blade shifting member which in the present 20 form comprises a slotted tube or sleeve 40 to the other end of which is affixed a spiral 41 preferably of different and certainly sufficient pitch to quickly flop the blade holder as hereinafter described. This spiral portion 35 41 passes through the slot 38 or angular aperture and thence has its end journaled in the end of the casing as at 42. As illustrated clearly in Fig. 3, the blade shifting member 40 is diametrically slotted along its 40 length to permit the blade 43 to project therethrough into contact with the stropping rolls. The blade carrier 44 in one form is shown as a rod knurled at its outer end at 45 to provide a gripping handle. Its inner end is provided with any suitable fastening means 46 engaging the slots of the tube 40 to prevent the complete withdrawal of the blade carrier 44. The blade carrier 44 and the slotted sleeve 40 constitute the blade 50 holder.

55 In the preferred form, the blade carrier 44 is cut away as at 47, leaving two upstanding studs or ears 48 and 49 adapted to pass through the holes 50 and 51 of the Gillette blade. The opposite end faces of the cut away portion 47 are beveled or inclined outwardly and downwardly as at 52 and 53 whereby to form a locking means to prevent inadvertent removal of the blade. In order to insert the 60 blade, it is bowed outwardly as in dotted lines of Fig. 6, and is then permitted to spring back to normal straight position and thus locked beneath the beveled end faces of the cut away portion. The end portion 32 is cut away as at 54 and 55 to permit the

withdrawal of the blade through that end of the basket. The casing 1 at this point is also provided with a slot 56 to permit the extraction of the blade through the end of the casing. This slot 56 and the slots 54 and 55 70 may be of any convenient size and design.

Referring again to the basket 29, it will be seen that it not only constitutes a rigid support for the rolls on the tubes or sleeves 2 and 3, but also forms a means cooperating 75 with the spiral 41 for positioning the blade 43 with respect to the rolls.

In operation, when the spiral driver 18, 19 is pulled outwardly, the first portion of the movement causes the balls 14 to 17 inclusive, to travel endwise of the slots 6 carrying the tubes 7 and 8, the rolls and basket 29 endwise of the casing. Since the blade holding tube 40 and its spiral portion 41 are held in the casing from endwise movement, the slot 38 in the basket travels along the spiral 41 to rotate the spiral and this oscillates the blade holding tube 40. This is the blade positioning movement. The blade is now positioned against the rolls. On further outward movement of the spirals 18 and 19, the balls are brought against the ends of the slots 6, at which time the spirals tend to turn the balls, which movement rotates the tubes or sleeves 2 and 3, and by 95 means of the pockets in the outer tubes 7 and 8 rotates the rolls 24 and 25.

As the ends of the spirals 18 and 19 reach their extreme outer position, the caps or stops 24 abut the balls and prevent further outward movement. When the spirals are reversed or pushed inwardly again, the initial movement permits the balls to move in the opposite direction along the slots 6 to reversely position the blade as before, and further movement of the spirals then rotates the rolls to produce the desired stropping action.

In the modification set forth in Fig. 8, the casing 60 is provided with the pairs of inwardly projecting tubes or sleeves 61 to 64, inclusive, which slidably support the reciprocal roll holding tubes 69 and 70. The inner ends or a suitable portion of these tubes 69 and 70 are indented or punched in as at 71 at spaced intervals circumferentially around the tubes to cooperate with the spirals 72 and 73 of the driver passing through these tubes. These spirals are united at one end by the handle 74 and at their opposite ends are provided with the stops 75 as before described. The blade holding tube 76 is constructed as hereinbefore described, being slotted to permit the blade 77 to project and is formed with a spiral portion 78 passing through a slot 79 in the basket 80. The outer end of the spiral is journaled as at 81 to the casing. If desired, suitable washers 82 or a shim may be located between the basket 80 and the ends 115 120 125 130

of the rollers to prevent their premature movement on reversal of the spiral driver. These washers or shims put a drag on the rolls. The operation of this modification is similar to the construction set forth in Fig. 1, except that the indented portions 71 replace the balls and slot drive of the former construction.

It is obvious that minor changes in the details of construction and the arrangement of the parts may be made without departing from the spirit of the invention as set forth in the appended claims.

Having thus described the invention, what I claim as new and desire to secure by Letters-Patent, is:—

1. A device of the class described comprising a casing, a tube journaled therein and reciprocating wholly within said casing, a stropping roll mounted on said tube, a blade holder mounted in said casing, a spiral driver reciprocable through said tube, and means operable by the reciprocation of said spiral driver for rotating and reciprocating the rolls and positioning said blade holder.

2. In a device of the class described, a casing, slotted sleeves journaled therein, a spiral driver reciprocable through said sleeves, a basket shiftable endwise along said sleeves, roll carrying sleeves carried within said basket and shiftable along said sleeves, rolls mounted on said roll carrying sleeves, means carried by said roll carrying sleeves and projecting through the slots in said tubes into contact with said spiral driver, a blade holder carried by said casing and operably connected with said basket to position said blade holder in timed relation to the rotation of said rolls by said driver.

3. A device of the class described comprising a casing, inwardly projecting sleeves carried by said casing, tubes carried by said sleeves for rotation and reciprocation entirely within said casing, a spiral driver reciprocable through said sleeves and tubes, stropping rolls rigidly carried by said tubes, a blade holder carried by said casing, and means operable on reciprocation of said driver for positioning said blade and rotating said rolls.

4. A device of the class described comprising a casing, stropping rolls and a blade shifting member mounted therein, means for positioning said blade shifting member and rotating said rolls, a blade holder non-detachably connected to said member and slideable into and out of said casing to blade sharpening position between the rolls or to blade removing position outside of said casing, said blade holder having means for positioning the blade thereon including under cut faces adapted to overhang opposite ends of the blade to prevent its inadvertent removal from the blade holder, beveled end-

faces adapted to prevent the inadvertent dislodgment of the blade.

5. A device of the class described comprising a casing, stropping means and a blade shifting member mounted therein, means for positioning said blade shifting member and rotating said rolls, a blade holder cooperating with said member and slideable relatively thereto into and out of said casing, said blade holder having means for positioning a blade thereon including a blade seat formed with a restricted mouth whereby when said blade is deformed or bowed, it can pass onto said seat and will then resume its natural flat form and will be locked thereon against inadvertent removal.

6. A device of the class described comprising a casing, a basket reciprocally mounted therein, stropping means journaled for rotation in said basket, a spiral driver reciprocable into and out of said casing, a blade holder having its opposite ends journaled in said casing and shiftable by the reciprocation of said basket, and means operable on the reciprocation of said driver for shifting said basket to position the blade holder, said means being adapted to thereafter rotate said stropping means.

7. A device of the class described comprising a casing, inwardly projecting sleeves carried by said casing, tubes mounted within said sleeves for rotation and reciprocation entirely within said casing, a spiral driver reciprocable through said sleeves and tubes, stropping rolls rigidly carried by said tubes, a blade holder carried by said casing, and means operable on reciprocation of said driver for positioning said blade and rotating said rolls.

8. A device of the class described comprising a casing, a basket reciprocably mounted therein, stropping rolls journaled for rotation in said basket, a spiral driver reciprocable into and out of said casing, a blade shifting member having a slotted tubular portion journaled for rotation in one end of said casing and having a spiral portion journaled for rotation in the opposite end of said casing, and passing through a slot in said basket, and means operated by said spiral driver for retaining the rolls and reciprocating the basket for positioning the blade shifting member.

9. A device of the class described comprising a casing, a pair of tubes journaled therein and reciprocating wholly within said casing, stropping rolls mounted on said tubes, a blade holder mounted in said casing, a spiral driver reciprocable through each tube, and means operable by the reciprocation of said spiral driver for rotating and reciprocating the rolls and positioning the blade holder.

In testimony whereof, I affix my signature.
GEORGE D. GALLAGHER.
